(57) **CLAIM**

We claim the ornamental design for a seafood utensil, as shown and described.

DESCRIPTION

FIG. 1 is a top plan view of the seafood utensil showing our new design;

FIG. 2 is a bottom plan view thereof;

FIG. 3 is a top perspective view thereof;

FIG. 4 is a bottom perspective view thereof;

FIG. 5 is a side perspective view thereof; and,

FIG. 6 is the opposite side perspective view of FIG. 5.
